UNITED STATES PATENT OFFICE.

JESSE M. WEBSTER AND CARL F. INGOLD, OF MILWAUKEE, WISCONSIN, ASSIGNEES TO THE MILWAUKEE OPTICAL MANUFACTURING COMPANY, OF MILWAUKEE, WISCONSIN, A CORPORATION OF WISCONSIN.

EYEGLASSES.

No. 873,109.

Specification of Letters Patent.

Patented Dec. 10, 1907.

Application filed April 16, 1906, Serial No. 311,876.

To all whom it may concern:

Be it known that we, JESSE M. WEBSTER and CARL F. INGOLD, both citizens of the United States, and residents of Milwaukee, in 5 the county of Milwaukee and State of Wisconsin, have invented certain new and useful Improvements in Eyeglasses; and we do hereby declare that the following is a full, clear, and exact description thereof.

10 Our invention relates particularly to nose-pieces for eye-glasses and has for its object to improve on what is set forth in Patent 628930, granted July 18, 1899, said invention consisting in what is herein shown, described and 15 claimed:

Figure 1 of the accompanying drawings represents a partly sectional rear elevation of one of our improved nose-pieces for eye-glasses on an enlarged scale and in connection with fragments of lenses; Fig. 2, a nose-side elevation of a portion of the device, the bridge of the same being in transverse section; Fig. 3, a perspective view of one of the 20 pivotal guards of the device in connection 25 with an arm having a spring extension by which the guard is controlled, and Fig. 4, a sectional view on the plane indicated by line 4—4 in Fig. 3.

Referring by letter to the drawings, A indicates an ordinary spring-bow bridge, the 30 ends of which are engaged with studs B attached to lenses C direct or constituting parts of frames for the lenses, as is common in the art. Each end of the bridge A is secured, 35 in connection with a stud B, by a screw D, and this screw also serves to hold the folded end of an arm E in engagement with the stud. The arm is of suitable curvature and a narrow outer portion E' thereof is a spring 40 parallel to the remainder of said arm and having yield transversely of the same from a point adjacent to the screw D by which an end of the bridge A and the folded portion of the aforesaid arm are held in engagement 45 with a lens or lens-frame stud. The lower end of the spring-extension E' of the arm E is connected, by a rivet F with a guard G, and the rivet has play in a slot H with which said arm is provided. The lower end 50 of the guard is preferably folded on that of the arm and a rivet I constitutes a pivotal connection between said guard and stiff portion of said arm.

The construction and arrangement of parts, as thus far described, is such that the guards 55 G of the nose piece normally project, for the most part, in rear of the remainder of said nose-piece, and are designed to support the eyeglasses in an easy and comfortable position on the nose of the person wearing same, 60 the necessary pressure being exerted by the bridge A aforesaid. When the eyeglasses are not in use the guards may be swung on their pivots I, against resistance of the spring-extensions E' of the arms E, so that the upper 65 ends of said guards will lie approximately within the plane of the lenses to economize space in an eyeglass case, the same as in the patent aforesaid, the particular features of our improvements being said arms having the 70 slots H and said spring-extensions, and the rivets F that play in the arm-slots and connect the aforesaid arm-extensions with the guards G that are in pivotal connection with the lower ends of the stiff portions of said arms. 75

Each guard G is preferably extended to fit up under the orbital arch of the wearer of the eyeglasses to thereby increase the bearing-surface, relieve pressure on the nose and prevent tipping of said eyeglasses, their hold on 80 the wearer being very much better than is ordinarily the case. The guards are also preferably apertured, to provide for better hold of same on the nose and under the orbital arch, the nose-aperture of each being a 85 reverse curve and of preferably greatest area at the upper end, this reverse curve of the aperture serving to insure against tipping of the eyeglasses when in use. It is also preferable to make the longitudinal edges of each 90 guard G concavo-convex in contour approximately parallel to the edges of the reversed curve nose-apertures in said guard, this construction serving to obtain clearance for the inner canthus of the eye and to obtain bearing 95 on the nose of the wearer of the eye-glasses where pressure will be the least objectionable.

The arms, their spring extensions and the guards being preferably of thin material, the pressure of the eyeglasses upon the nose of 100 the wearer is elastic and said guards are in a measure self adjusting and thus automatically conformable to said nose, their connection with said arms being such that they have ready yield in one direction under pressure 105 instead of being distorted.

We claim:—

1. The combination with the studs of eyeglass lenses or frames of same, the spring-bow bridge-piece, slotted arms each having a fold 5 held with an end of said bridge-piece in engagement with one of said studs, the outer portion of each arm being a spring; a nose-guard in pivotal connection with the lower stiff portion of each arm, and a spring-and-10 guard connecting rivet having play in the slot with which the stiff portion of the arm is provided.
2. The combination of the eyeglass studs, the spring-bow bridge-piece, slotted arms each 15 having a fold held with an end of said bridge-piece in engagement with one of said studs, the outer portion of each arm being a spring; a nose-guard in pivotal connection with the lower stiff portion of each arm and having a 20 reverse curve aperture longitudinally thereof as well as concavo-convex longitudinal edges approximately parallel to the edges of said aperture, and a spring-and-guard connecting

rivet having play in the slot with which the lower stiff portion of each arm is provided. 25

3. The combination of the eyeglass studs, the spring-bow bridge-piece, slotted arms each having a fold held with an end of said bridge-piece in engagement with one of said studs, the outer portion of each arm being a 30 spring; a nose-guard in pivotal connection with the lower stiff portion of each arm and extended to fit up under the orbital arch of the wearer of the glasses; and a spring-and-guard connecting rivet having play in the 35 slot with which the stiff portion of each arm is provided.

In testimony that we claim the foregoing we have hereunto set our hands at Milwaukee in the county of Milwaukee and State of 40 Wisconsin in the presence of two witnesses.

JESSE M. WEBSTER.
CARL F. INGOLD.
